CLAIM

The ornamental design for a module frame for a water treatment system controller, as shown and described.

DESCRIPTION

FIG. 1 is a front perspective view of a module frame for a water treatment system controller in accordance with an embodiment;

FIG. 2 is a front elevation view of the module frame for a water treatment system controller in accordance with the embodiment;

FIG. 3 is a rear elevation view of the module frame for a water treatment system controller in accordance with the embodiment;

FIG. 4 is a left side elevation view of the module frame for a water treatment system controller in accordance with the embodiment;

FIG. 5 is a right side elevation view of the module frame for a water treatment system controller in accordance with the embodiment;

FIG. 6 is a top plan view of the module frame for a water treatment system controller in accordance with the embodiment; and,

FIG. 7 is a bottom plan view of the module frame for a water treatment system controller in accordance with the embodiment.

Any broken lines shown in the figures are for the purpose of illustrating portions of the module frame which form no part of the claimed design.
